STUDENT CARREL

Norman R. Selinger, 401 Southlawn Lane,
Rockville, Md. 20850

Filed Dec. 27, 1974, Ser. No. 536,745

Term of patent 3½ years

Int. Cl. D6—99

U.S. Cl. D6—181

The figure is a perspective view of a student carrel, showing my new design.

The back of the article is plain and unornamented, while a perspective view taken from the right front of the carrel would be a mirror image of the view shown.

I claim:

The ornamental design for a student carrel, as shown and described.
